UNITED STATES PATENT OFFICE

2,078,400

INSULATED SANITARY COVER FOR MILK CANS

Kenneth A. Maupin, Eaton Rapids, Mich.

Application June 27, 1936, Serial No. 87,810

8 Claims. (Cl. 150—52)

This invention relates to insulating sanitary covers for milk cans and the like. Heretofore in transporting milk cans it has been necessary to buckle on cumbersome stiff covers of hair felt or the like with handles thereon for handling the cans. Such covers are of excessive weight due to the necessity for the buckles and straps and are unsatisfactory in that they must be stiff and formed in order to properly contain the can which makes the storage of these covers quite a problem.

The objects of this invention are:

First, to provide an effectively closed insulated can cover which protects and insulates a milk can and which does not interfere with the handling of the can during hauling or shipment.

Second, to provide such a structure which is provided with effective provision for handling the can while keeping it sealed and protected from dirt and infiltration of heat.

Third, to provide such a can cover with an improved insulating material whereby the weight of the article is materially reduced.

Fourth, to provide an improvement in the insulating material itself.

Fifth, to provide such a can cover which may be compactly folded and stacked and stored with the greatest of ease.

Sixth, to provide such a can cover which may be conveniently placed on the can and removed and will allow the loading of more cans in a given floor space.

Seventh, to provide such a can cover which effectively keeps out all dirt and insects and which may be turned inside out for airing and washing.

Eighth, to provide such an insulating cover which may be made very inexpensively and is more efficient than the can covers heretofore employed.

I accomplish the objects of my invention by the structure described in the following specification and illustrated in the accompanying drawing, in which:

Fig. 1 is a perspective view of a milk can with my improved insulating structure in position thereon, the milk can being entirely covered and concealed thereby.

Fig. 2 is an enlarged detail elevation partly in section through the can and its handles, showing the details of construction and how the can may be handled with my insulating cover thereon.

Fig. 3 is a detail sectional view through the insulating cover showing the construction 55 thereof.

Fig. 4 is a view of my cover off the can and folded in position for storage.

In the drawing, 1 is the usual metallic milk can with the reduced neck at the top and the usual handle 2 thereon. 3 is my improved insulating cover. It is an open bottom bag closed at the top having double walls 4 and 5 preferably made of waterproofed canvas. The bag is of a size to fit snugly over the head of a milk can and in the sides of the bag opposite the location of the handles of a can enclosed therein I provide extra fullness forming a pair of closed pockets 6 which can be tucked over and around the handles of a milk can as shown in Fig. 2, so that the handle may be grasped with my cover in place as shown in Fig. 2. The hands of a person handling the can are shown at 7. With this arrangement I make possible the grasping of the can by the handles 2 already provided thereon without any openings through which dirt or insects may pass or through which heat infiltration may take place.

Between the double walls of my protector, I provide insulating material 8. In the center of the insulating material I provide a sheet 9 of "cellophane" or regenerated cellulose which is impervious to the air. The sheet shown is reinforced by thread 10 woven in the form of a mesh and with this sheet it is possible to prevent infiltration of the air even though the outer fabric 4 or the inner fabric 5 of the protector may become torn. The insulating material 8 which I employ is a wool bat which I produce in a woolen mill especially for this purpose. The wool is thoroughly cleansed to make it lively and resiliant. I cross the fibers in the arrangement so that it will be permanently retained in position between the outer wall 4 and the inner wall 5 of the structure. I prefer to retain this bat in place by suitable quilting stitching 11 although it will be appreciated that when I refer to quilting I am referring to stapling or other suitable means for holding the padding in place between the double walls.

The structure I have produced is like an inverted sack, adapted to seal around the can on the floor or platform at the bottom. I put an annular row of quilting stitches 12 near the bottom, forming a special annular filled section 13 at the bottom, which contacts with the floor and spreads out and makes practically an air-tight and vermin-tight joint at that point; also the protector fits the can closely and is entirely closed and stitched closed at the top. It is thus proof against insects or contamination. At points to 45

the front and rear of the can I quilt-stitch a central pad 14 which serves to retain the outer wall and the lining in proper relation to this filling material.

5 The air is confined within by this double wall and the insulation is thus maintained. Air is also confined about the top to the container in the space 15. It will be apparent that my structure eliminates a change of air about the can and 10 over the milk, thus eliminating the possibility of bacterial contamination from outside.

At the top I stitch in a loop 16 which serves as the handle for the structure. The structure can be turned inside out for cleansing, sterilizing or 15 repair. I have shown the structure as applied to a milk can. It will protect any similar can. I do not show a bottom. One could be provided. The protector is very efficient without it and is used in that form.

20 I desire to claim the invention in its specific form and also broadly as in the appended claims.

Having thus described my invention, what I claim as new and desire to secure by Letters Patent is:

25 1. A protector for a milk can or the like having handles, comprising an open-bottom closed-top bag formed of double walled fabric, said bag being of a size to fit snugly over the body of a milk can or the like and having at the sides thereof opposite the location of the handles of a can enclosed therein an extra fullness forming a pair of closed pockets to be tucked under and about the handles of a milk can whereby the can is protected and the handles may be grasped by the 30 hands, and insulating material, and a sheet of air impervious material enclosed between the double walls of said bag in the portions of the bag other than said pockets, and a row of quilting stitches in proximity to the bottom of said bag 40 to form a tubular part adapted to contact with the floor around the bottom of the can to form a seal.

2. A protector for a milk can or the like having handles, comprising an open-bottom closed-top bag formed of double walled fabric, said bag being 45 of a size to fit snugly over the body of a milk can or the like and having at the sides thereof opposite the location of the handles of a can enclosed therein an extra fullness forming a pair of closed pockets to be tucked under and about the handles of a milk can, whereby the can is protected and the handles may be grasped by the 50 hands, and insulating material enclosed between the double walls of said bag in the portions of the bag other than said pockets, and a row of quilting stitches in proximity to the bottom of said bag 55 to form a tubular part adapted to contact with the floor around the bottom of the can to form a seal.

3. A protector for a milk can or the like having 60 handles, comprising an open-bottom closed-top bag formed of double walled fabric, said bag being of a size to fit snugly over the body of a milk can or the like and having at the sides thereof opposite the location of the handles of a can 65 enclosed therein an extra fullness forming a pair

of closed pockets to be tucked under and about the handles of a milk can, whereby the can is protected and the handles may be grasped by the hands, and insulating material and a sheet of air impervious material enclosed between the double walls of said bag in the portions of the bag other than said pockets.

4. A protector for a milk can or the like having handles, comprising an open-bottom closed-top bag formed of double walled fabric, said bag being of a size to fit snugly over the body of a milk can or the like and having at the sides thereof opposite the location of the handles of a can enclosed therein an extra fullness forming a pair of closed pockets to be tucked under and about the handles of a milk can, whereby the can is protected and the handles may be grasped by the hands, and insulating material enclosed between the double walls of said bag in the portions of the bag other than said pockets.

5. A protector for milk cans or the like having handles consisting of a double walled fabric bag sealed at the top and open at the bottom, the same adapted to fit snugly the body of the milk can and enclose an air space around the top, the said walls being of waterproof construction, a wool bat filling, the fibers having been crossed, disposed between the walls of the said protector with the exception of the area just beneath the handles, which consist merely of the double fabric, the walls being flexible and of sufficient fullness and adapted to be deflected under the handles, whereby the handles can be grasped by the hands within the protector without hand holes.

6. A protector for milk cans or the like having handles consisting of a double walled fabric bag sealed at the top and open at the bottom, the same adapted to fit snugly the body of the milk can and enclose an air space around the top, the said walls being of waterproof construction, an insulating filling disposed between the walls of the said protector with the exception of the areas just beneath the handles, which consist merely of the double fabric, the walls being flexible and of sufficient fullness and adapted to be deflected under the handles, whereby the handles can be grasped by the hands within the protector without hand holes.

7. A protector for a milk can or the like having handles, consisting of a double walled bag, having padding between the walls, closed at the top, the padding being distributed between the said double walls except an area just below each handle of the protected can, said unpadded area having sufficient fullness to be deflected under said handles.

8. A protector for a milk can or the like having handles comprising a double walled bag having a fullness located opposite the handles of a can 60 enclosed therein forming a pair of closed pockets to be tucked under and about the handles of such can, and padding distributed between said double walls except in said pockets.
